UNITED STATES PATENT OFFICE.

MORITZ J. PFAFF, OF PITTSBURGH, PENNSYLVANIA.

HAND DRILLING-MACHINE.

1,207,999.

Specification of Letters Patent. Patented Dec. 12, 1916.

Application filed November 22, 1915. Serial No. 62,801.

To all whom it may concern:

Be it known that I, MORITZ J. PFAFF, a citizen of the United States of America, residing at Pittsburgh, in the county of Allegheny and State of Pennsylvania, have invented certain new and useful Improvements in Hand Drilling-Machines, of which the following is a specification.

The present invention relates to an improved hand drilling machine, and more particularly to the supporting frame or attachment used in connection with the drilling machine, by which the latter may with facility be converted for use as a bench drill, as a typical breast drill, or with equal facility and effectiveness be utilized for special purposes.

The primary object of the invention is the provision of an attachment or supporting frame for the drill which will be adapted for a wide variety of uses, which is durable, economical, and efficient, and which is simple in its construction and manipulation.

With these objects in view the invention consists in certain novel combinations and arrangements of parts as will be more fully pointed out in the following specification and claims.

In the accompanying drawings I have illustrated one complete example, adapted to three different uses, of the physical embodiment of my invention constructed according to the best mode I have so far devised for the practical application of the principles of my invention.

Figure 1 is a side elevation of a drill and its supporting frame according to my invention, adapted for use as a typical bench drill. Fig. 2 is a front view of the device of Fig. 1. Fig. 3 is a view similar to Fig. 2, but with the drill omitted for clearness of illustration. Fig. 4 is a side view of so much of the device as to indicate its use as a type of breast drill. Fig. 5 is a horizontal sectional view on line 1—1 Fig. 3. Fig. 6 is a sectional view on line 2—2 Fig. 3. Fig. 7 is a rear view of a portion of the frame at line 5—5 Fig. 1. Fig. 8 is a sectional view on line 4—4 of Fig. 1. Fig. 9 is a sectional view on line 3—3 of Fig. 3. Fig. 10 shows the drill and its supporting frame adapted for special use as will be described hereinafter. Fig. 11 shows a modified form of joint between the sections of the supporting frame.

For the purpose of illustrating the con-

struction and operation of my invention I have utilized a typical form of drilling machine of the hand type, embodying the drill or bit 1, the drill chuck 2 which are of usual or suitable type, and the drill also includes the gear wheel 3 of the bevel type which is in mesh with the bevel pinions 4 and 5, the latter revoluble on stem 8 and serving as an idler or guide pinion, and the former 65 rotating with the chuck 2, and the whole being supported by the slideable shank 6. A detachable crank handle 7 is employed to turn the bevel gear to operate the drill, and the upper portion of the stem 8 is attached to the screw feed bar 9 by means of the perforated sleeve 10 and cotter pin 11. The sleeve 10 is rigid with the screw bar 9 and the stem fits into the sleeve so that the cotter pin is passed through aligned perforations in these two elements. The feed of the drill is accomplished in usual manner by revolving the hand wheel 12.

When used as a bench drill or for many special purposes, the drilling machine is supported in my novel frame as shown in Figs. 1, 2, 3, and 10. In Fig. 1 it will be seen that the frame is a sectional one, comprising a pair of upright bars 13 and 14 with a mortise and tenon joint at 15 and a screw bolt 16 to clamp the parts together and make a rigid and stable joint.

The upper end of the top section 13, it will be seen is bent at right angles to form a bearing 17 for the feed screw bar 9, and the offset portion 18 of this section forms an abrupt bend or shoulder 19 arranged at right angles to the plane of the lower portion of this section. When used as a bench drill the drill is supported directly 95 from this angle bracket 17 and the offset portion 18, and for this purpose the shank 6 of the drill is held to the frame through the slot 20 in the portion 18 and the set screw 21. This slot it will be understood permits the required movement of the drill spindle when so actuated by the feed screw bar 9. At the edges of the front side of the portion 18 oppositely disposed wings or flanges 22, 22, are provided as guides and retainers for the shank in its relationship with the frame.

The work holding plate 23 located directly below the drill or bit 1 is a circular disk with a screw bar 24 and a locking screw or pin 25. The bar is threaded into the angle bracket 26 which is detachable

from the frame section 14, and the angle bracket is loosely attached to the U-shaped portion 26' of the section 14 by a mortise and tenon joint as indicated at 27 in Fig. 5 1. The section 14 is fashioned with a pair of integral lugs 28 to form a depression or seat 29 for the horizontal portion of the angle bracket 26. By means of the screw bolt 30 the drilling machine and its frame 10 are attached or clamped to the bench 31 through the medium of the U-shaped portion of the frame section 14.

To convert the bench type of drill into a breast type of drill, the supporting frame 15 is omitted and the feed screw bar 9 is also omitted and in its stead the stem 8 is fitted into a sleeve 32 of the breast plate 33, and an extra or special handle 7 is fixed to the spindle by utilizing the threaded opening 20 which accommodates the screw 21 when the drill is used at a bench.

A special use of the drill and its supporting frame is illustrated in Fig. 10. Here the lower section of the frame has been disconnected from section 13 by withdrawing the lock nut or bolt 16, and the work plate 23 is used as a foot plate against the object to be drilled, while its screw bar 24 threaded in the perforated boss 34 of the section 13 25 adjusts the support in connection with the wooden or other brace 35. This brace bar 35 it will be seen rests at one end on the shoulder 19 of section 13, and at its other end is in contact with a suitable support. 30 The brace bar is held to the frame section 35 by clamping means comprising a yoke 36 and clamp bolt 37, and an additional bolt 38 at the side of the frame opposite to the bolt 37 insures and permits adjustment between the frame and brace bar.

In Fig. 11 the ends of the two frame sections 13' and 14' have at their joint, teeth as 13^a and 14^a which mesh with each other and provide an additional feature to insure 45 stability of the joint. The perforated lug 34' is the same as the lug 34 in the other views.

Copies of this patent may be obtained for five cents each, by addressing the "Commissioner of Patents, Washington, D. C."

From this description taken in connection with my drawings it is evident that the device is capable of use for purposes of various natures and that it may be converted to its several uses with facility and despatch. When used as a bench drill it is rigidly attached or supported by the use of the U-frame 26' and the drilling machine itself 50 is supported with stability in its supporting frame, the two points of support at 17 and 18 being adequate for holding and maintaining the device in position for doing its work in a workmanlike manner. The 55 rounded cross sectional formation of the shank 6 which rests in the curved space between the two flanges 22, 22 insures a uniform and straight line movement of the shank as the feed screw is turned by the 60 hand wheel.

Other meritorious features will be apparent to those skilled in this art, and need not be pointed out at this time.

What I claim is:—

1. The combination in a drilling machine of the bench type including its screw feed bar and slidable shank, of a supporting frame and means for clamping it to a bench, an angle bracket on the frame for supporting the screw feed bar, and said frame having a slotted offset portion provided with side flanges to receive the shank, and a set screw passed through the slotted portion and the shank for retaining the latter. 70 75 80

2. The combination in a drilling machine including its screw feed bar and slidable shank of a frame section having an angular bracket for the feed bar and said frame having an offset slotted portion forming a 85 shoulder and means in connection with said offset portion for guiding and retaining the shank, a supporting brace bar adapted to engage said shoulder, a perforated lug on the frame section, and a foot plate having 90 a screw bar engaging said lug.

In testimony whereof I affix my signature.

MORITZ J. PFAFF.
